SLIDER FOR SEPARABLE FASTENERS

Davis Marinsky, Bronx, N. Y., assignor to White-hall Patents Corporation, New York, N. Y., a corporation of New York

Application September 10, 1935, Serial No. 39,908

8 Claims. (Cl. 24—205)

This invention relates to separable slide fasteners employing stringers for coupling links or elements adapted to be coupled and uncoupled and a slider movable longitudinally of the stringer for coupling and uncoupling the same, and particularly to the construction of the slider employed in devices of this kind; and the object of the invention is to provide a slider, preferably in the form of a die cast body including an integrally formed hook portion which is fashioned to form a coupling loop with which a finger piece or pull may be quickly and easily attached, and by means of which the operation of attaching the finger piece or pull is facilitated; and with this and other objects in view, the invention consists in a device of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a plan view of a part of a separable fastener showing one of my improved sliders thereon and indicating one method of its use.

Fig. 2 is a view similar to Fig. 1, eliminating part of the construction and on an enlarged scale.

Fig. 3 is a partial section on the line 3—3 of Fig. 2.

Fig. 4 is a view similar to Fig. 1 showing a slight modification; and,

Fig. 5 is a side view of a slider detached with a part thereof in normal or open position.

In the accompanying drawing, I have indicated at 10 and 11 two stringers of a separable fastener having coupling links or elements 12 and 13 attached to adjacent beaded edges 10a, 11a respectively. At 14, I have indicated an end stop for limiting the movement of a slider or rider 15 in one direction on the links 12, 13 of the stringers.

The slider 15 is preferably formed from a single die cast body consisting of an upper side plate 16 and lower side plate 17 joined by a substantially V-shaped web 18 at one end of the slider and to form at said end of the slider diverging channels 19 and 20 which join each other within the body and through the reduced end portion 21 of the slider as in other devices of this kind. The side edges 16a, 17a are turned inwardly

adjacent each other to form flanges which serve to urge the links 12 and 13 toward each other and to hold said links in coupled relation within the reduced end portion 21. Formed integrally with the top plate 16 of the slider is a hook-shaped finger piece supporting member 22, the end portion 22a of which extends normally in a plane substantially parallel to the surface of the top plate and in the direction of the reduced end portion 21 of the rider in the manner indicated in Fig. 5 of the drawing.

In the construction shown in Figs. 1 to 3 inclusive, I have indicated a pull chain 23 in the form of a single chain element having a ring or eye 24 at one end and a large ball or knob 25 at the other end. Whereas, in Fig. 4 of the drawing, the finger piece or pull 23a differs from that shown in the other figures simply in employing a longer ball-like chain having two loops or eyes 24a at the ends and a ball 25a arranged centrally of the chain. The chain 23a forms a ring or loop through which the finger of the hand may be passed in the operation of the slider.

The slider and stringers shown in Fig. 4 are of the same structure as that shown in Fig. 1, and therefore, like references will designate like parts. It will be understood that the slider is die cast substantially in the manner shown in Fig. 5 of the drawing, it being understood that in some cases, the side flanges 16a, 17a will be shaped or extended inwardly by suitable dies after the casting operation. However, in coupling the finger piece or pull with the hook 22 of the rider, the loop or eye of the pull, or in other words, the apertured piece 24, 24a, is passed over the end portion 22a of the hook when in the position indicated in Fig. 5 of the drawing, after which the end portion 22a is forced downwardly upon the upper surface of the top plate 16 to form the closed coupling loop shown, which retains the pull against displacement from the slider and at the same time, permits the free swinging movement of the finger piece so as to extend in the direction shown in Figs. 1, 2 and 3 of the drawing in the operation of opening the fastener as well as in a position directly opposite that shown, which position will be assumed by the finger piece in the operation of closing the fastener. In other words, it is preferred that the finger piece or pull operate upon the permanently attached end of the loop 22 when the slider is operated under the stress of closing

the fingers and upon the end portion 22a when the slider is moved into open position.

With a slider constructed in the manner described, the operation of attaching or coupling the finger piece or pull with the slider is accomplished in a very simple and effective manner, and at the same time, a strong and durable coupling is provided for the finger piece or pull. Still further, by virtue of the formation of the slider from a unitary body of die cast material, the same may be produced very economically.

Having fully described my invention, what I claim as new and desire to secure by Letters Patent, is:

15. 1. In separable fasteners employing fastener stringers adapted to be coupled and uncoupled, a slider movable longitudinally of the stringers for coupling and uncoupling the same, said slider comprising a molded body of unitary construction having opposed side plates with channels between said plates through which the stringers are adapted to pass, the outer surface of one of said side plates being relatively flat and having an integral projecting hook including a free end portion extending in a plane substantially parallel to the outer surface of said plate and in spaced relation thereto.

30. 2. A slider for separable fasteners of the class described comprising a unitary body of molded material having channels extending therethrough diverging at one end of said body and converging at the other end thereof, the side edges of the slider having inwardly extending flanges arranged in spaced relation to each other, the outer surface of one side wall of the slider being substantially flat and provided centrally thereof with a hook-shaped member integral with said body at one end of said member, the free end portion of said member being arranged 35 in spaced relation to said surface and arranged longitudinally thereof, and said hook-shaped member providing means for attaching a finger piece or pull with said slider.

35. 3. A slider for separable fasteners of the class described, said slider comprising a unitary molded body the outer surface of one side wall of which is flat and provided with an integral coupling loop arranged within the boundary edges of said wall, one end only of said loop being integrally 40 united with said wall, and the other end being arranged in abutting relation to said wall.

45. 4. A molded slider for separable fasteners of the class described, one side wall of the slider having a longitudinally straight outer surface, a semi-circular loop projecting from the central portion of said surface and extending longitudinally thereof, said loop being round in cross sectional form one end portion of said loop being integral with said side wall, and the other end 50 portion thereof being unattached and in abutting relation with said wall.

55. 5. In separable fasteners employing fastening stringers adapted to be coupled and uncoupled, a slider movable longitudinally of the stringers for coupling and uncoupling the same, said slider comprising a molded body of unitary construc-

tion having opposite side plates, with channels between said plates through which the stringers are adapted to pass, the outer surface of one of said side plates being relatively flat and having an integral projecting loop, the free end portion 5 of the loop extending in the direction of the plate to form in conjunction therewith a closed loop and a finger piece coupled with said loop.

6. In separable fasteners employing fastening stringers adapted to be coupled and uncoupled, a slider movable longitudinally of the stringers for coupling and uncoupling the same, said slider comprising a molded body of unitary construction having opposite side plates with channels between said plates through which the stringers 10 are adapted to pass, the outer surface of one of said side plates being relatively flat and having an integral projecting loop, the free end portion of the loop extending in the direction of the plate to form in conjunction therewith a closed loop 15 and a finger piece coupled with said loop, said finger piece comprising a flexible chain having an enlarged ball at one end portion thereof, and said chain including side portions extending from said ball, the free ends of which being mounted 20 upon the coupling loop of said slider.

7. A slider for separable fasteners of the class described comprising a unitary body of molded material having channels extending therethrough diverging at one end of said body and converging 30 at the other end thereof, the side edges of the slider having inwardly extending flanges arranged in spaced relation to each other, the outer surface of one side wall of the slider being substantially flat and provided centrally thereof with a 35 loop-shaped member integral with said body at one end of said member, said loop-shaped member providing means for attaching a finger piece or pull with said slider, and the free end portion of said loop-shaped member being arranged upon the outer surface of said side wall of the slider to form a closed coupling loop retaining the finger piece coupled with said loop against displacement therefrom.

40. 8. A slider for separable fasteners of the class described comprising a unitary body of molded material having channels extending therethrough diverging at one end of said body and converging 45 at the other end thereof, the side edges of the slider having inwardly extending flanges arranged in spaced relation to each other, the outer surface of one side wall of the slider being substantially flat and provided centrally thereof with a 50 loop-shaped member integral with said body at one end of said member, said loop-shaped member providing means for attaching a finger piece or pull with said slider, the free end portion of said loop-shaped member being arranged upon the outer surface of said side wall of the slider to form a closed coupling loop retaining the finger piece coupled with said loop against displacement therefrom, and said finger piece having an apertured end portion capable of free movement into positions to engage opposite end portions of said coupling loop.

DAVIS MARINSKY.
